(57) **CLAIM**

The ornamental design for a reversible canine coat, as shown and described.

DESCRIPTION

FIG. 1 is a right side elevation view of a reversible canine coat showing my new design;

FIG. 2 is a left side elevation view thereof;

FIG. 3 is a front elevation view thereof;

FIG. 4 is a rear elevation view thereof.

FIG. 5 is a top plan view thereof;

FIG. 6 is a bottom plan view thereof;

FIG. 7 is a right side elevation view thereof showing the reversible canine coat in a reversible position; and,

FIG. 8 is a left side elevation view thereof showing the reversible canine coat in a reversible position.

The dash lines represent stitches and form a part of the claimed design.
